June 29, 1962. This application June 1, 1965, Ser. No.
466,499

4 Claims. (Cl. 2-3)

This application is a substitute of my prior application S.N. 206,273, filed June 29, 1962, now abandoned.

The invention relates to a head protective device and particularly to a safety cap of unique and novel design for use by industrial, commercial workers and the like.

Those familiar with safety devices generally will understand that in industrial and commercial activities it is desirable that the worker utilize a suitable head protecting device to avoid accidental injury while engaged in his occupation. For example, telephone men frequently are required to enter rather tight crawl spaces and the like in homes or other buildings to accommodate service installation. While moving in these confined quarters, these individuals are frequently subjected to accidental bumps on the head which are not only personally irritating, but subjects such persons to potential injury. In other active professions such as for example, aircraft assemblers and service men, a high degree of mobility again in confined quarters is required. Here protective head devices also avoid injury due to accidental head bumping or accidental contact with swinging beams, jibs, or other operating equipment.

While avoiding potential injury to the user, protective devices heretofore employed in the art have presented many disadvantages. Characteristically, the devices were composed of a hard shell which, though satisfactory from a safety standpoint, have been found to be uncomfortable and difficult to wear by the operator over an extended period of time. Furthermore, head gear of this prior art type has been found difficult to size properly and, accordingly, not readily adaptable to the varying shaped heads of individual workers. Users frequently complained of discomfort, headaches, and the like.

A specific disadvantage of the prior art protective head gear relates to the utilization of such equipment in connection with the service of aircraft. In aircraft and missile servicing, it is well known that many highly sophisticated and volatile fuels are utilized. This type of fuel, because of its inherent volatility, provides an ever present danger of accidental fire and explosion. The heretofore utilized hard plastic safety caps were found to be disadvantageous in that they tended to surface-store static electrical charges much the same as an electrical condenser. Frequently, these electrical charges would be built up in a given head gear merely as a result of the frictional contact between the head gear and the surrounding air moving thereover. The hazard is obvious. The existence of such a static charge and the possibility of spark-to-ground in a volatile atmosphere is always present.

The present invention obviates all of the mentioned difficulties in that it provides a safety cap of unique design which initially is readily adaptable to head contours of varying form and, accordingly, extremely comfortable to wear. Further, the design employs a unique structural arrangement which positively prohibits the accidental storage of static charge thereon, yet offering a maximum degree of head protection required in many day-to-day occupations.

These and other objects and features of the invention will become apparent in the course of the following description and from an examination of the drawings, wherein:

2

FIGURE 1 is a top plan view of a typical safety cap constructed in accordance with the instructions;

FIGURE 2 is a top plan view of a half section of a cap similar to FIGURE 1 but with the cloth cap covering removed; and

FIGURE 3 is a vertical sectional, side elevational view of the cap shown in FIGURE 1.

Describing the invention in detail and directing attention to the figures, it will be noted that the cap arrangement comprises a central liner 2, said central liner 2 being generally cup-shaped, preferably to the general configuration of a human head. In the preferred embodiment of the invention, the liner 2 is made of a plastic material, it being found that a suitable type plastic known under the trade name "Marlex" is satisfactory for the functions hereinafter described. The liner 2 is delineated by a lower edge 4, the edge 4 preferably falling in a uniform plane defining the lower terminus of the liner. In addition, the liner 2 is provided with a plurality of slots 6, 8, 10 and 12 formed therein preferably equal angular spacing around the entire periphery of the liner. It will be understood that, in the half section view of FIGURE 2, only four of the slots are illustrated, but that the other half segment of the cap is identical with that here illustrated, the slots 6 and 12 being partially shown. Each of the slots 6, 8, 10 and 12 break the lower edge 4 of the liner 2 and extend radially inwardly of the liner 2 as seen in plan view approximately two-thirds of the distance of the liner from lower edge 4 to the apex 14 thereof. It will be understood that the formation of the respective slots is an important feature of the invention and that the depth of the slots within the liner 2 may be of varying degree, it having been found that the approximate two-thirds distance mentioned provides a very satisfactory structure, both from the standpoint of wearer comfort and protection.

The liner 2 may further be provided with a forwardly-projecting plastic visor 16, said visor 16 in the preferred embodiment being a separate plastic part and not integrally connected to the liner 2. However, if desired, the plastic visor may be connected in any suitable manner to the liner 2.

Adjacent the lower edge 4 of the liner 2, the latter is provided with a plurality of radially outwardly-projecting studs 18, 18, the studs 18 providing suitable means for attaching a cup-shaped formed cloth cover 20. The cloth cover 20 is formed to complement the general contour of the liner 2 and intimately overlie the upper surface thereof. The cloth cover 20 is further provided with snap fasteners 22 which may be of any conventional design and which claspingly receive the studs 18 on the plastic liner 2. In this manner, the cup-shaped cloth cover 20 is fixedly secured to the liner 2 and completely covers the upper surface thereof.

As an additional feature of the invention, the cloth cover 20 may be provided around its lower angular edge with a bead 24. The bead 24 may be slightly tensioned within the cloth cover 20 so that it tends to snap-underlie the lower edge 4 of the liner 2 and retain the cloth cover on the latter uniformly around the entire lower periphery of the liner 2. The bead 24 may, of course, be stretched within the cover 20. Thus, bulges of the plastic liner 2 intermediate the snaps 22 are eliminated, thus enhancing appearance as well as assuring complete coverage of the internal liner 2.

To provide uniform appearance and further to completely cover all of the plastic liner 2, the cloth cover 20 may be provided with an appropriate visor section 30, the latter extending downwardly over the surface of the plastic visor 16 and therearound upwardly as at 32 to cover the lower surface of the visor 16. The cloth visor segments 30 and 32, of course, may be sewn or otherwise

fixedly secured to the cloth cover 20 in any conventional manner.

To materially enhance the comfort of the safety cap illustrated, it has been found desirable to provide on the inner side of the plastic liner 2 and at the central dome thereof a suitable annular segment of cushion material 34 such as sponge rubber or the like. The central segment 34 is provided with a plurality of uniformly-radiating cushion material 36, 36 extending therefrom and preferably underlying each of the respective slots 6, 8 10 and 12. An annular band of sponge material 38 is positioned on the inner surface of the liner 2 and immediately adjacent to the lower terminal edge 4 thereof. The radial spokes 36, 36 communicate with the annular band 38, in association with the central segment 34, 15 provide an appropriate soft cushion to comfortably engage the head of any wearer.

It will be understood that the cushion material 34, 36 and 38 may be secured to the inner surface of the liner 2 in any suitable manner such as, for example, by utilizing an appropriate resin, glue or the like.

Considering for the moment the unique features and desirable advantages of the structure just described, it will be understood that the provision of a plastic liner 2, when the safety cap is in use, as well as the employment of the cushion material on the undersurface of the liner 2, acts as a safety member to resist virtually any normal accidental blow to the head of the wearer. It will also be noted that the plastic liner 2 uniformly covers virtually the entire upper portion of the wearer's head. 30 In this manner, the desired protection is afforded for virtually all normal occupational hazards.

As a particular feature of the described arrangement, it will be recalled that the liner 2 is provided with a plurality of segments 40, 40 disposed annularly therearound, 35 each defined by the immediately adjacent slots 6, 8, 10 and 12, etc. The segments 40 are thus connected to the central or dome portion of the liner 2 in a cantilever manner and each will independently and resiliently spring from the central segment 14 to a degree and without material effect on adjacent segments. From a comfort standpoint, the independent spring characteristics of the respective segments 40 provide the unique structure which readily accommodates or forms the entire protective cap to the head of a given wearer regardless of his particular cranial contour. With this structure, it has been found that a safety cap of the disclosed arrangement can be worn by a worker for extended periods of time without the discomfort incident to prior art arrangements.

The segmented construction of the liner 2 and the resulting independent spring action of the respective segments 40 also provides for the improved safety efficiency thereof in that the spring action per se tends to absorb and resist accidental blows to each of the segments 40. Thus, an important portion of the force from a given accidental blow is absorbed by the spring action of the cantilever segment 40 actually engaged. As noted above, the structure of the plastic liner 2 functions satisfactorily both from the standpoint of comfort and safety when the slots are formed approximately two-thirds of the surface distance from the terminal edge 4 of the liner to the dome.

A further feature of the invention which not only aids in the appearance thereof but is important from a functional standpoint relates to the provision of a cloth cover 20 over the entire surface of the plastic liner 2. The provision of the cloth cover positively prevents the accidental build-up of any static electrical charge on the liner 2 while in service. Patently, with the structure shown, the liner is continuously shielded from the frictional charging effect of moving air. In this connection, it will be recalled that the bead 24 aids in preventing exposure of any part of the plastic liner 2. Additionally, in the preferred embodiment illustrated, the plastic visor 16 is also completely covered with the cloth material as at 30

and 32. Thus, the hazard of accidental spark discharge, especially in the locale of volatile fuels that was incident to the heretofore employed head safety devices is entirely eliminated.

It is also important to provide some ventilation within the cap. The slots 6, 8, 10 and 12 permit this ventilation of the cap even though the slots have cushion material 36 over the slots since such cushion material can be of the open cell type which permits "breathing" of the material, i.e. flow through of air.

The cap may have the obvious modification of a non-continuous dome structure if the primary protection of the wearer is desired at the side areas of the head; and the cushioning material may be circular strips inside the cap similar to the band 38 but positioned higher in the cap extending crosswise of the slots.

The invention is shown by way of illustration and not limitation and may be subject to modifications without departing from the scope of the appended claims.

I claim:

1. In a safety cap arrangement to be worn by a user to protect the user's head and being retained on the user's head solely by the cap arrangement, including:
  - (a) a one-piece liner formed of relatively hard and resilient plastic material; said liner being permanently molded in a crown shape generally conforming in configuration to the user's head;
  - (b) said liner having a central section located at the top of the liner and positioned on the top of the user's head;
  - (c) at least four cantilever segments independently attached to and extending outwardly and downwardly from said central section, each segment terminating at a lower edge and the lower edges of the segments being laterally aligned with each other, each segment being separated from adjacent segments by a narrow slot extending radially of said liner;
  - (d) each of said slots extending at least about one-half and less than about two-thirds the distance from the lower edge of the segment to the middle of the central section;
  - (e) each of said segments being permanently formed to the general shape of the user's head in the area covered by the segments;
  - (f) each segment being resilient and swingable in a spring action relative to the central section and relative to each other to adapt the liner for various sizes and shapes of user's heads, and said liner being held on the user's head solely by the segments snugly receiving the user's head;
  - (g) a fabric cover material intimately encompassing said liner and generally engaged with the entire outer surface of the liner, the spring action of said segments maintaining the fabric cover material taut on the liner, such that the liner shapes the fabric cover material, a bead affixed to the peripheral edge of the fabric cover material, and said bead being snap-positioned in a tensioned condition beneath the lower edges of the segments to maintain the fabric cover material taut on the liner.
2. In a safety cap arrangement according to claim 1 wherein:
  - (a) at least eight segments are independently attached to and extend from said central section.
  - (b) means on the fabric cover material to fasten the lower edge of the cloth cover material to each stud.
3. In a safety cap arrangement according to claim 1 including:
  - (a) at least one stud extending outwardly from the lower end of each segment, and,
  - (b) means on the fabric cover material to fasten the lower edge of the cloth cover material to each stud.
4. In a safety cap arrangement according to claim 1 including:
  - (a) strips of cushion material affixed to the inside of the liner and completely overlying said slots.
